UNITED STATES PATENT OFFICE.

SIDNEY C. WILSON, OF PENN YAN, NEW YORK, ASSIGNOR TO WILSON PROCESS, INCORPORATED, OF ROCHESTER, NEW YORK, A CORPORATION OF NEW YORK.

PROCESS OF SHOE MANUFACTURE.

1,424,745.

Specification of Letters Patent. Patented Aug. 1, 1922.

Application filed April 25, 1918. Serial No. 230,633.

To all whom it may concern:

Be it known that I, SIDNEY C. WILSON, a citizen of the United States, and resident of Penn Yan, in the county of Yates and 5 State of New York, have invented an Improvement in Processes of Shoe Manufacture, of which the following description, in connection with the accompanying drawings, is a specification, like letters on the 10 drawings representing like parts.

The usual process of manufacturing shoes, speaking generally without reference to particular types of shoes, consists in assembling the insole and upper of a shoe on a last, 15 performing the various "making" operations on the shoe parts so assembled and then performing the finishing operations on the shoe. The term "making" is here used in the sense in which it is employed in the 20 trade to designate those operations by which the upper and the shoe bottom are permanently secured together and the shoe is made ready for the finishing operations. In the performance of certain of these making operations it is necessary to have the 25 stock "in temper"; that is in the condition in which it contains sufficient moisture or some other softening agent to keep it soft and pliable. It is found, however, that even 30 if the stock is in temper when the shoe is assembled, it hardens rapidly during the process of manufacturing, and it usually is necessary to perform several tempering operations on the shoe or parts thereof before 35 the making operations are completed. It is one of the chief objects of this invention to improve the processes of manufacturing shoes with a view to eliminating much of the trouble heretofore experienced 40 in conditioning the stock for the manufacturing operations.

The invention is also concerned particularly with the processes of manufacturing shoes of the McKay type. The usual 45 method of manufacturing shoes of this construction is to assemble an insole and an upper on a last, last the upper over upon the outer face of the insole, and secure it in this position by tacks which are driven through the upper and insole and clinched at the inner face of the insole. The outsole is then laid, the shoe is removed from 50 the last, and the upper, insole and outsole

are then secured together by sewing. The shoe is then heeled, and finally the finishing 55 operations are performed on it.

While this type of shoe has many merits which are well recognized by those skilled in this art, as, for instance, the fact that it can be manufactured very economically and 60 that a stronger inseam can be made in it when a relatively poor insole is used than in other types of shoes, it is also open to certain rather serious objections, such as the fact that the bottom is relatively stiff and inflexible, due partly to the presence of the clinched lasting tacks, and also that it is 65 much less comfortable than other types of shoes, due both to the presence of the inseam stitches on the inner surface of the 70 insole and also to the fact that the lasting tacks are liable to work up as the shoe becomes worn and make themselves exceedingly troublesome. It is therefore a very 75 important object of this invention to so improve the process of manufacturing McKay shoes that these objections above noted will be substantially eliminated, and to enable the lasting tacks to be removed while the 80 upper and insole are still held together by temporary holding means, which, however, may be left in the shoe, and while it is held thus and the lasting tacks removed, the last is withdrawn and the permanent 85 stitching is inserted. Heretofore in the making of McKay shoes the lasting process has been performed either by clinching the 90 lasting tacks on a metal plate, or by not using any lasting tacks whatever, relying on lacing, cementing or the like. In my 95 process I employ the lasting tacks, but only drive them temporarily into the insole and last, carrying out exactly the process, and preferably with the machines, used in making welt shoes, wherein the lasting tacks 95

are removed, after the inseaming operation. My shoe relies upon the through and through or McKay stitching only for its permanent 100 sole attaching means, and not upon a plurality of such stitching, i. e., both inseam and outseam, as in welt shoe manufacture. By my present process the lasted upper and insole are temporarily held together for the short time required to remove the lasting 105 tacks, withdraw the last, and put in the permanent stitching which extends through

and through both insole, upper materials and outsole. Thus I am enabled to carry out my process of making a tackless McKay shoe.

5 The manner in which it is proposed to accomplish these objects will be readily understood from the following description and the novel features will be particularly pointed out in the appended claims.

10 Referring now to the accompanying drawings,

Fig. 1 is an angular view of a last which preferably is employed in practising the process of this invention;

15 Fig. 2 is an angular view of an insole prepared for incorporation in a shoe;

Fig. 3 is an angular view of the shoe after it has been partially lasted;

20 Fig. 4 is a transverse cross sectional view through the forepart of the shoe shown in Fig. 3 on the line 4—4, Fig. 3, and showing the parts on a larger scale than in Fig. 3;

Fig. 5 is a cross sectional view similar 25 to Fig. 4 but showing the shoe at a later stage in the process of manufacture; and

Fig. 6 is a cross sectional view showing the shoe after the stitching operation has been completed.

30 In carrying out the process of this invention a last preferably is employed of the type disclosed in my co-pending application filed of even date herewith. This last is of the construction shown in Figs. 1 and 4, 35 and is unique in that its sole supporting face is centrally recessed to receive a layer 3 of felt or similar moisture-retaining material. Surrounding this central covering 3 of felt is a marginal face 4 of suitable 40 width to receive the lasting tacks. The last also is provided with the usual anvil plate 5 at the heel seat against which the heel seat nails can be clinched.

The insole 6 is fitted for incorporation in 45 a shoe by channelling it, as indicated at 7, Fig. 2, to receive the inseam, turning back the channel flaps 8 and coating these flaps with some suitable cement. This insole is then placed on the last 2 with the channelled 50 face of the insole against the bottom face of the last as clearly shown in Fig. 4, the insole being held on the last by tacks 9. The upper 10 of the shoe, the various parts of which have previously been sewed together 55 in the usual way, is next placed on the last and is held on the last by a tack 11. This completes the assembling operations and the shoe is now ready for the making operations.

60 The first of the latter operations consists in lasting the shoe and this process may be performed by hand or with the aid of the known commercial machines. For the purpose of reducing manufacturing costs and 65 making use of the commercial machines

with which the operatives are familiar, it is proposed to depart from the usual method of lasting McKay shoes and to perform this operation in two steps in the same general manner that welt shoes are lasted at 70 the present time. That is, by performing first the pulling over operation and second, the lasting operation, using the term "lasting" in its specific sense rather than in its generic sense.

75 As is well understood by those skilled in this art the commercial pulling over machines are designed to perform the preliminary lasting operations at the toe part of the shoe and they have means for simultaneously grasping the upper at a plurality of points around the toe, pulling this portion of the upper into lasted position, and driving several tacks through the upper and insole to secure the upper in this position. 80 In Fig. 3 five such tacks 12 are shown at the toe portion of the shoe. The side and heel lasting operations may then be performed on the usual hand method lasting machine which operates in a step by step 85 manner around the shoe, the shoe being held in the hands of the workman. This machine preferably is set to drive the tacks in front of the heel seat, which are indicated at 13, only partially into the shoe so that 90 they may later be pulled out; but the tacks 14 at the heel seat are driven in firmly and clinched against the anvil plate 5. Before the lasting operation is started the lower marginal portion of the upper which 95 is to be lasted over upon the bottom face of the insole is coated with a suitable cement, or other adhesive compound as indicated at 15, Fig. 3, and the margin of the bottom face of the insole may also be coated at this 100 time if desired. Figs. 3 and 4 show the shoe after the lasting operation has been partially completed, some portions of the upper still remaining to be turned down over the bottom face of the insole.

110 After this operation has been completed and the coated marginal portion of the upper has been laid over in its final position on the outer face of the insole around the entire edge of the sole the shoe is allowed 115 to rest for several hours in order to become set or conformed to the last and to give the cement or other adhesive compound that secures the margin of the upper to the insole an opportunity to set. All the tacks in 120 front of the heel seat are then removed and, since these tacks have been only partially driven in, this operation can be very readily performed. The outsole 16, Fig. 5, which may have been channelled or not as 125 desired, is then "laid"; that is, temporarily secured to the bottom of the insole and the overlaid upper by cement. The last is then withdrawn from the shoe leaving the shoe in the condition shown in Fig. 5 in which it 130

is ready for the inseaming operation. This operation may be performed by hand or by any suitable McKay stitcher.

At this point it may be stated that an important feature of this process is the maintaining of the insole in temper while the making operations are being performed, so that when the shoe is removed from the last in readiness for the stitching operation 10 the insole will be in proper condition for this operation, and no re-tempering of the insole will be required. This function is performed by the felt cover 3 (although it is obvious that it might be performed by 15 other means) it being merely necessary to moisten the felt member 3 thoroughly before the insole is secured to the last in the course of assembling the shoe. Since the outsole is in temper when it is laid, it is 20 obvious that the shoe is ready for the stitching operation as soon as the last is pulled. Moisture also is supplied to the channel flap by the felt piece 3 so that this flap is maintained in suitable condition to be turned 25 down over the stitches of the inseam as soon as the shoe has been sewed. Furthermore, the provision of the felt covering under the channel flap affords a cushion for the flap and mechanically protects it against breaking 30 during the making operations. Immediately after the shoe has been sewed to make the inseam 17, Fig. 6, the channel flap 8 is turned down over the stitches of the inseam, the cement on the flap having been 35 maintained in a tacky, adhesive condition during the entire process of making the shoe by the moisture supplied to the adhesive coated face by the felt cover 3. The channel flap therefore can be turned down in its 40 final position as shown in Fig. 6 without any preliminary tempering operation and because of being in a very soft and pliable condition there is no danger of breaking the lip during the channel laying process. The 45 outsole channel flap is then turned down, the heel is attached to the shoe, and the finishing operations are performed in any desired manner.

It will now be evident that the process devised by this invention produces an improved shoe construction in which all the advantages of the McKay shoe as now constructed are retained while the disadvantages due to the presence of the lasting tacks 50 in the shoe are eliminated. At the same time the step of supplying a tempering agent to portions of the interior of the shoe while the making operations are being performed effects a saving both in the elimination of 55 injury, which otherwise might result to the parts of the shoe that are thus kept in a soft and pliable condition, and in avoiding 60 the necessity for retempering these portions of the shoe. The cushioning of the channel 65 flap also reduces the liability of injury to

this part of the shoe. This process produces a shoe having a smooth inner surface for contact with the foot and one devoid of tacks or other metallic fastenings in front of the heel seat. While the invention has 70 been herein disclosed in connection with its application to a shoe of the McKay type, it is obvious that certain features of the process are equally applicable to other types of shoes, particularly welts and turns; and the 75 term "insole," therefore, is used herein to designate not only the insole of a McKay or welt shoe but also the sole of a shoe of a turn or other type in which a single sole only is used. 80

I believe that my process of making shoes, as herein described, particularly the method of making a shoe of the McKay type employing through and through stitching and eliminating all tacks throughout the fore- 85 part and shank, utilizing a wooden last without a tack-clinching plate or anvil on the forepart and shank and therefore utilizing a welt shoe pulling-over and lasting machine, is a distinct novelty and of great 90 advantage and I wish to claim the same broadly. This process results in the manufacture of the shoe embodying all the advantages, economies, and strength incident to a McKay shoe type together with the 95 manufacturing advantages, better lasting and fitting qualities, and flexibility of a welt shoe type producing a tackless McKay shoe which is claimed in my said co-pending application. 100

What is claimed as new, is:

1. That improvement in the process of manufacturing shoes, which consists in channelling an insole, turning back the channel flap, assembling said insole and an upper 105 on a wooden last with the channeled face of the insole next to the bottom face of the last supplying a tempering agent to the channel flap, and performing the making operations on the shoe. 110

2. That improvement in the process of manufacturing McKay shoes, which consists in channelling an insole on its inner face for the reception of the inseam, turning back the channel flap, assembling said insole and an upper on a last, working the upper into lasted position on the outerface of the insole, cementing the lasted upper in said position on the outer face of the insole, applying removable lasting tacks to hold the 120 lasted upper, removing the last, running the inseam in said channel to secure the outsole, insole and upper together, turning the channel flap down over the inseam and securing it in said position, and then completing the 125 manufacture of the shoe in any desired manner.

3. The improved process of making a tackless McKay shoe, which consists in providing a last having a recess to receive, con- 130

ceal and protect the flap of an insole, assembling the insole thereon with the marginal flap turned backwardly to house in said recess, applying an upper and lining, lasting the shoe by partially driving in lasting tacks, temporarily securing the shoe upper and insole by adhesive along the shank and forepart, withdrawing the lasting tacks, applying the outsole, withdrawing the last, 10 sewing through the outsole, upper and insole around the marginal portions of shank

and forepart while the insole flap is still turned outwardly, then turning down the insole flap and completing the shoe.

In testimony whereof, I have signed my 15 name to this specification, in the presence of two subscribing witnesses.

SIDNEY C. WILSON
